SOCKET FOR VACUUM TUBES AND THE LIKE

William H. McKee, Park Ridge, Ill., assignor to Cinch Manufacturing Corporation, Chicago, Ill., a corporation of Illinois

Application January 12, 1956, Serial No. 558,757

4 Claims. (Cl. 339—75)

The present invention relates to improvement in electrical socket members and particularly to the general form adapted to receive and make electrical connection with a pronged electronic tube.

In conventional socket members heretofore known in the art, the forces provided by the socket contacts for gripping the tube terminals have been inherent in the spring metal of the contacts which is usually hardened to effect a stiffer action. It has been found with this type of contact that the resilient prong-engaging portions have a tendency to set after repeated insertions and withdrawals of a vacuum tube with the result that the contacts lose their effectiveness for making positive tensioned engagement with the tube prongs.

An object of the present invention is to provide a socket member having contact members for receiving prong terminals constructed in such a way that the terminals are received by the contact members without the necessity of applying insertion forces. At the same time the construction of the socket device effects strong withdrawal forces.

Another object of the invention is to effect a socket member in which an external force is applied to a prong-engaging portion of the contact members thereby providing positive electrical engagement between the contact members and the tube prongs which eliminates reliance upon the inherent spring characteristics of the metal of the contact members.

Other objects and uses of my invention will be apparent from an inspection of the accompanying drawing and annexed specification in which I have illustrated and described a preferred embodiment of my invention.

In the drawings:

Fig. 1 is a top view of my improved socket device,

Fig. 2 is a bottom view of the socket device,

Fig. 3 is a side view of the socket device showing the contact actuating member in closed position,

Fig. 4 is a view similar to Fig. 3 with the contact actuating member in open position,

Fig. 5 is a section taken on the line 5—5 of Fig. 1 with the contact actuating member in closed position, and

Fig. 6 is a section similar to Fig. 5 with the contact actuating member shown in open position.

Referring to the drawings, my socket device comprises an insulating body 1 having a top end face 2 and a bottom end face 3. The upper portion 4 (Fig. 5) of the body 1 is of greater diameter than the lower portion 5 so as to form a peripheral overhang 6. The top end face 2 has a series of prong-receiving openings 7 which are arranged in a generally circular configuration. The bottom end face 3 has a bore 8 formed therein which terminates adjacent the bore 8 has a series of elongated openings 10 positioned in complementary relation to the openings 7 in the top face 2 and intersecting the same. The openings 10 extend axially of the socket body 1 and terminate short of the bottom face 3 to form shoulders 11.

As a means for attaching the socket devices to a sup-

2

porting panel, a metal saddle member 12 is provided as part of the socket assembly. The saddle member 12 has a central opening 13 in which the insulating base 1 is disposed. Movement of the body 1 through the opening 13 in one direction is limited by the overhang 6 of the body 1 which engages the upper surface 14 of the saddle member 12. The saddle member 12 has a pair of oppositely disposed wing portions 15 which engage the body 1 adjacent the top end face 2 to limit relative movement of the parts in an opposite direction. The saddle member 12 has an opening 16 disposed adjacent the central opening 13 to receive a locking arm of the contact actuating member in a manner to be described. The saddle 12 has an opening 17 at each of opposite ends for receiving a rivet member (not shown) for attaching the socket device to a supporting panel.

The body 1 carries a plurality of socket contact members each of which is disposed within an opening 10 and its complementary aperture 7. Each of the contact members 18 in my preferred form is formed from a single piece of bendable, ribbon-like metal folded intermediate its ends to provide a pair of legs 19 and 20 having their broad surfaces in adjacent relation. The leg portions 19 and 20 are joined together by a bight 21 (Fig. 3) and are bent slightly at a point spaced from the bight to form a shoulder element 22 (Fig. 6) for engagement behind the bottom end face 3 when the parts of the socket device are in assembled relation. The leg element 20 has a laterally-extending portion 23 integrally joined to the end of the leg 20 away from the bight 21 and arranged to bottom on the shoulder portion 11 of the body 1 when the parts of the socket are in assembly. The leg 20 has a straight arm portion 24 integrally joined to the end of the laterally-extending portion 23 and disposed within the openings 10 and 7 adjacent the body portion 1. The leg portion 19 has a prong-engaging element 25 which extends upwardly in generally parallel relation to the arm portion 24. The element 25, in my preferred form, has a bowed portion 26 projecting in the direction of the arm element 24 and a second bowed portion 27 which projects into the bore 8 for a purpose to be described. The free end 28 of the element 25 is disposed within the aperture 7 of the top end face 2 and is preferably flared outwardly away from the arm element 24 to effect a lead for receiving a tube prong 29 between the prong-engaging element 25 and the arm portion 24. It will be noted that substantially no forces are exerted by the element 25 and arm 24 during insertion of the tube prong 29 between the same. As a result, those forces are eliminated which are inherent in conventional spring contacts and which under certain conditions tend to bend the tube prongs during the insertion action.

As a means for exerting external force on the prong-engaging portions of the contact members for effecting positive electrical engagement with a tube prong, I have provided an actuating body 30 which is formed of insulating material and shaped and arranged for complementary reciprocating movement within the bore 8 of the body 1. As a means for moving the actuating body 30 in and out of closed position within the body 1, I have provided a metal locking member 31 having a generally straight bar portion 32 which is disposed laterally of and extends above the actuating body 30. The lower end 33 of the bar 32 has a foot portion 34 (Fig. 2) which is preferably molded into the actuating body 30. During movement of the body 30 into closed position the portion 35 of the foot portion 34 which is disposed externally of the actuating body 30 will be received within an axial slot 36 formed in the end face 3 of the body 1 and communicating for its entire length with the bore 8 of the body 1. The bar 32 extends through the opening 16 of the saddle 12 when the parts are in assembly

and provides laterally-extending shoulders 37 for engagement with the upper surface 14 of the saddle 12 for a purpose to be described. The bar 32 has an integral spring tongue 38 in predetermined spaced relation with respect to the shoulders 37 and extending out of the plane of the bar 32. The tongue 38 has a depressed portion 39, adjacent its free end for fastener engagement with a wall 40 of the opening 16 of the saddle member as will be described.

Relationship of the parts of the socket device when the actuating body is in open position is illustrated in Fig. 6. Thus, the upper end 41 of the actuating body 30 is disposed adjacent the bottom end 3 of the body 1 in alignment with the bore 8. The actuating body 30 is maintained in this position by means of the shoulders 37 which engage the upper surface 14 of the saddle 12 adjacent the opening 16. As a result of the fact that the diameter of the actuating member 30 is only slightly less than the diameter of the bore 8, the upper end 41 of the actuating body 30 operates to maintain the contact members in position within the openings 10 of the body 1 as shown in Fig. 6. Prior to movement of the actuating body 30 into closed position the tube prongs 29 are moved through the openings 7 of the body 1 to bottom against the shoulder elements 23 of the contact members between the prong-engaging portions 24 and 25 of the respective contact members. The actuating body 30 is moved into closed position within the bore 8 by a pull force exerted on the bar 32. During this action, the upper end 41 of the actuating body 30 will engage the bowed portion 27 of the element 25 of the contact member to force the element 25 positively against the tube prong 29. When the actuating body 30 is in full closed position with its end 41 adjacent the abutment 9 of the body 1, the spring tongue 38 which has been depressed during the closing movement will expand to engage the depression 39 with the wall 16 of the saddle 12 thereby locking the actuating body 30 in position to clamp the element 25 against the tube prong. As a result of this clamping action, strong withdrawal forces prevent unintentional disengagement of the tube prongs. When it is desired to release pressure of the contact members upon the tube prongs to withdraw the tube, manual pressure is applied to the bar 32 in a downward direction to release the spring tongue 38 thereby permitting the actuating body 30 to return to open position.

Although I have illustrated and described a preferred embodiment of my invention, I do not wish to be limited thereby as the scope of my invention is best defined by the following claims.

I claim:

1. An electrical socket comprising a body of insulating material having top and bottom end faces, said body having a plurality of prong-receiving openings extending into said top end face, said body having a bore extending into said bottom end face and terminating adjacent an abutment, said body having an inner wall adjacent said bore, said inner wall having a plurality of contact-receiving openings communicating with said prong-receiving openings, contact members disposed in said contact-receiving openings, each of said contact members having a pair of prong-engaging elements for engaging between them a terminal prong, one of said prong-engaging elements having a laterally projecting portion extending into said bore, and a second insulator body assembled with said first body and arranged for reciprocating movement endwise of said body within said bore, said second insulator being adaptable for movement toward said abutment to engage said laterally-projecting portion thereby to force said first prong-engaging element toward the other of said prong-engaging elements.

2. An electrical socket comprising a body of insulating material, a saddle member assembled with said body having an opening in which said body is disposed, said body having top and bottom end faces, said body having a plurality of prong-receiving openings extending into said top end face, said body having a bore extending into said bottom end face and terminating adjacent an abutment, said body having an inner wall adjacent said bore, said inner wall having a plurality of contact-receiving openings communicating with said prong-receiving openings, contact members disposed in said contact-receiving openings, each of said contact members having a pair of prong-engaging elements for engaging between them a terminal prong, one of said prong-engaging elements having a laterally projecting portion extending into said bore, and a second insulator body assembled with said first body and arranged for reciprocating movement endwise of said body within said bore, said second insulator being adaptable for movement toward said abutment to engage said laterally-projecting portion thereby to force said first prong-engaging element toward the other of said prong-engaging elements.

5 3. An electrical socket comprising a body of insulating material, a metal saddle assembled with said body having an opening in which said body is disposed, said body having top and bottom end faces and a plurality of prong-receiving openings extending into said top end face, said body having a bore extending into said bottom end face and terminating adjacent an abutment, said body having an inner wall adjacent said bore, said inner wall having a plurality of contact-receiving openings communicating with said prong-receiving openings, contact members disposed in said contact-receiving openings, each of said contact members having a pair of prong-engaging elements for engaging between them a terminal prong, one of said prong-engaging elements having a laterally-projecting portion extending into said bore, and a second insulator body assembled with said first body and arranged for reciprocating movement endwise of said body within said bore, said second body being adaptable for movement toward said abutment to engage said laterally-projecting portion thereby to force said first prong-engaging element toward the other of said prong-engaging elements to engage under pressure a terminal prong inserted between said prong-engaging elements, said second insulator body having an element projecting through said saddle for manually moving said second insulator into closed and open positions, and said element and said saddle having cooperating fastener means for maintaining said second insulator in closed position.

10 4. An electrical socket comprising a body of insulating material, a metal saddle assembled with said body having an opening in which said body is disposed, said body having top and bottom end faces and a plurality of prong-receiving openings extending into said top end face, said body having a bore extending into said bottom end face and terminating adjacent an abutment, said body having an inner wall adjacent said bore, said inner wall having a plurality of contact-receiving openings communicating with said prong-receiving openings, contact members disposed in said contact-receiving openings, each of said contact members having a pair of prong-engaging elements for engaging between them a terminal prong, one of said prong-engaging elements having a laterally-projecting portion extending into said bore, and a second insulator body assembled with said first body and arranged for reciprocating movement endwise of said body within said bore, said second body being adaptable for movement toward said abutment to engage said laterally-projecting portion thereby to force said first prong-engaging element toward the other of said prong-engaging elements to engage under pressure a terminal prong inserted between said prong-engaging elements, an actuating element assembled with said second insulating body and extending through said saddle member, said actuating element and said saddle member having cooperating means holding said second body in open position relative to said bore prior to reciprocating movement of said second body within said bore to engage said laterally-projecting portion of said prong-engaging element.

15 5. A device of the type described in claim 3 in which said actuating element and said saddle member have cooperating fastener means for holding said second body in closed position with said second body in engagement with said laterally-extending portion of said prong-engaging element.
